William Gordon Inventor

By his Attorney
Joseph D. O'Brien

UNITED STATES PATENT OFFICE.

WILLIAM GORDON, OF UNION, NEW JERSEY.

MONKEY-WRENCH.

1,380,794.

Specification of Letters Patent. Patented June 7, 1921.

Application filed October 20, 1919. Serial No. 331,952.

To all whom it may concern:

Be it known that I, WILLIAM GORDON, a citizen of the United States, and a resident of the town of Union, county of Hudson, 5 and State of New Jersey, have invented certain new and useful Improvements in Monkey-Wrenches, of which the following is a specification.

This invention relates to improvements in 10 monkey wrenches, and particularly to that type of monkey wrenches in which exceeding nicety and fineness of adjustment is procured by the engagement with a rack of a plurality of movable members adapted alternately to be moved into and out of 15 engagement with the rack and to split up or subdivide the space between the teeth of the rack.

One of the objects of this invention is to 20 produce an engagement between the rack and one of such engaging members which will be firm and secure and will enable the employment on each engaging member of a plurality of teeth adapted to engage the 25 rack simultaneously.

Another object is to provide a wrench construction in which the angle of inclination of the engaging member or members to the rack will be decreased and the pivot or 30 pivots thereof lowered relatively to the plane of the rack; thus greatly increasing the effective grip of such engaging members with the rack and enabling the engaging members and their teeth to withstand 35 greater strain when the wrench is in use, and also preventing a slipping or flying-out of engagement of the teeth of the engaging member with the teeth of the rack.

Another object of my invention is to produce 40 a wrench in which the rack-engaging members are connected with the shank of the wrench at one end of such members; are released by engagement with a lifter at the opposite end and have their engaging-teeth 45 positioned intermediate the ends of the members.

Another object of my invention is to produce 50 a wrench of the character above described having relatively few parts capable of ready assembly, and to this end to provide the stationary member with a stationary jaw at one end, a suitable shank and a socket for the engaging members including at the rear end of said stationary member a

bearing or connecting socket for the rear 55 ends of the engaging members, while the movable jaw is provided with an integral rack and the rack-engaging members are retained in relatively stationary position on the stationary member. 60

With these and other objects in view, the invention comprises the combination of members and arrangement of parts so combined as to co-act and coöperate with each other in the performance of the functions 65 and the accomplishment of the results herein contemplated, and comprises in one of its adaptations the species or preferred form illustrated in the accompanying drawings, in which:

Figure 1 is a side elevation, partly in section, of a wrench embodying my invention;

Fig. 2 is a section on the line 2—2 of Fig. 1;

Fig. 3 is a section on the line 3—3 of 75 Fig. 1;

Fig. 4 is a section on the line 4—4 of Fig. 1; and

Fig. 5 is a diagrammatic view showing the relationship of the various engaging 80 members to the rack.

Referring now to these drawings which illustrate a preferred embodiment of my invention, 1 indicates the shank of the wrench having a stationary jaw 2 at one end, and 85 3 indicates the movable jaw which is slidable on said shank and has formed integrally therewith a rearwardly projecting rack 4 having teeth 5 disposed inwardly toward the shank. The shank 1 is provided with an 90 elongated socket 6 extending from a point midway between the ends to the opposite end of said shank and terminating in a socket 7 serving as an anchor for rack-engaging members 11 mounted on the stationary shank. The movable jaw 3 is, as shown, normally drawn to its rear position by a spring 8 stretched between a stationary eye 9 on the shank and another eye 10 on the rack 4, and seated in the elongated socket 6 of 100 the shank are a series, and preferably three, rack engaging members 11, each of which has at the rear end a rounded anchoring knob 12, a long inclined shank 13, a rack or series of teeth 14 contiguous to the opposite end thereof and is also provided at its opposite end with a shoulder 15 adapted to be engaged by a lifter 16. The en- 105

gaging member 11 and other parts are all assembled in the rear or handle end of the wrench and a casing 17 is slid over the same and suitably connected in position to inclose 5 all the parts and retain the same in their relative operative positions.

The rack-engaging members 11 may be held in contact with the rack teeth 5 by a spring 18 having divided legs which press 10 against the members 11 individually, but, if desired, the rack-engaging members may be made of resilient metal and this spring omitted.

The operation of the wrench is as follows: 15 Assuming that the wrench is in position shown in Fig. 1 with the teeth or rack on one of the engaging members held in engagement with the teeth of the rack on the movable jaw and it is desired to operate with 20 a wrench on a larger nut, the lifter is engaged by the fingers of the user and all of the engaging members are simultaneously disengaged from the rack, whereupon the spring 8 will cause the movable jaw 5 to be 25 instantaneously moved to its full open position. The jaw may then by manual engagement therewith be moved into suitable nut engaging position, during which operation the teeth on the various engaging members 30 14 will click over the teeth of the various racks until the proper position is reached.

The wrench by reason of the fact that it embodies a series of engaging members 14 disposed one alongside of the other and in 35 such relationship to the rack as to subdivide or split the space between a tooth thereof will permit a fine adjustment to be made and a tight grip to be obtained upon the nut or other device which it is desired to 40 manipulate.

Having described my invention I claim:

1. In a monkey wrench, the combination with a fixed jaw and a movable jaw, one of 45 which is provided with a rack having teeth extending inwardly and the other with a shank having a rack engaging member provided with a series of teeth extending outwardly and adapted to engage the said rack, said rack engaging member comprising an 50 arm extending rearwardly and having a connection at the rear end of the shank, and means at the front of the wrench for actuating said rack-engaging member.

2. In a monkey wrench, the combination 55 with a fixed jaw and a movable jaw, one of which is provided with a rack having teeth extending inwardly and the other with a shank having a rack engaging member mounted in said shank and provided with a 60 series of teeth adapted to engage the said rack, said rack engaging member having at one end an elongated rearwardly disposed arm connected with the stationary shank, and a forwardly extending shoulder at the 65 opposite side of the teeth of said rack en-

gaging member, and means projecting in the same direction as the jaws of said wrench for releasing said rack engaging member.

3. In a monkey wrench, the combination with a fixed jaw and a movable jaw, one of 70 which is provided with a rack having teeth extending inwardly and the other with a shank having a rack engaging member mounted in said shank and provided with a series of teeth adapted to engage the said 75 rack, said rack engaging member having at one end an elongated rearwardly disposed arm connected with the stationary shank, and a forwardly extending shoulder at the opposite side of the teeth of said rack 80 engaging member and a manually actuated lifter adapted to engage said shoulder, and having its actuating portion extending in the same direction as the said jaws and to the rear side of said rack. 85

4. In a monkey wrench the combination with a fixed jaw and a movable jaw, one of which is provided with a rack having teeth extending inwardly and the other with a shank having a series of rack engaging members 90 mounted in said shank, each rack engaging member being provided with a series of teeth, the teeth of the series of rack engaging members being so disposed relatively to the rack as to subdivide the interdental 95 space and procure fineness of adjustment combined with rigidity of gripping action, each rack engaging member comprising an arm extending rearwardly and having a connection at the rear end of the shank, and means projecting in the same direction as the jaws of said wrench for releasing said 100 rack engaging member.

5. In a monkey wrench the combination with a fixed jaw and a movable jaw, one of 105 which is provided with a rack having teeth extending inwardly and the other with a shank having a series of rack engaging members mounted in said shank, each rack engaging member being provided with a series 110 of teeth, the teeth of the series of rack engaging members being so disposed relatively to the rack as to subdivide the interdental space and procure fineness of adjustment combined with rigidity of gripping action; each rack engaging member having at one 115 end an elongated rearwardly disposed arm connected with the stationary shank, and a forwardly extending shoulder at the opposite side of the teeth of said rack engaging members, and means projecting in the same direction as the jaws of said wrench for releasing said rack engaging member. 120

6. In a monkey wrench the combination with a fixed jaw and a movable jaw, one of 125 which is provided with a rack having teeth extending inwardly and the other with a shank having a series of rack engaging members mounted in said shank, each rack engaging member being provided with a series 130

of teeth, the teeth of the series of rack engaging members being so disposed relatively to the rack as to subdivide the interdental space and procure fineness of adjustment
 5 combined with rigidity of gripping action; each rack engaging member having at one end an elongated rearwardly disposed arm connected with the stationary shank, a forwardly extending shoulder at the opposite
 10 side of the teeth of said rack engaging members and a manually actuated lifter adapted to engage said shoulders, and having its actuating portion extending in the same direction as the said jaws and to the rear side of
 15 said rack.

7. A monkey wrench comprising a shank provided with a fixed jaw, a movable jaw slideable on said shank, a rack formed integral with said jaw and having teeth extending inwardly, a rack engaging member mounted in said shank and provided with a plurality of teeth adapted to engage said rack, and means projecting in the same direction as the jaws of said wrench for releasing said
 25 rack engaging member.

8. A monkey wrench comprising a shank provided with a fixed jaw, a movable jaw slideable on said shank, a rack formed integral with said jaw and having teeth extending inwardly, a plurality of rack engaging members mounted in said shank and provided with a plurality of teeth adapted to engage said rack, and means projecting in the same direction as the jaws of said wrench for releasing said rack engaging member.

9. A monkey wrench comprising a shank provided with a fixed jaw, a movable jaw slideable on said shank, a rack formed integral with said jaw and having teeth extending inwardly, a rack engaging member connected to said shank and provided with a plurality of teeth adapted to engage said rack, a spring stretched between said shank and rack for normally retaining the jaws in separated positions and means projecting in the same direction as the jaws of said wrench for releasing said rack engaging member.

10. A monkey wrench comprising a shank provided with a fixed jaw at one end, another jaw movable relatively to said fixed jaw on said shank, a rack associated and movable with said movable jaw and having teeth extending inwardly, and a rack-engaging member having a portion connected adjacent to the end of the shank opposite to the fixed jaw; a series of teeth on said member extending parallel to the said rack and an elongated inclined portion intermediate

said series of teeth and the portion connected to said shank, and means projecting in the same direction as the jaws of said wrench for releasing said rack engaging member.

11. A monkey wrench comprising a shank provided with a fixed jaw at one end, another jaw movable relatively to said fixed jaw on said shank, a rack associated and movable with said movable jaw and having teeth extending inwardly, a rack-engaging member having a portion connected adjacent to the end of the shank opposite to the fixed jaw; a series of teeth on said member extending parallel to the said rack and an elongated inclined portion extending from said shank to a toothed portion, said toothed portion and shank connecting portion being disposed at a distance from each other to provide a decreased angle of inclination between the rack and connection with the shank, and means projecting in the same direction as the jaws of said wrench for releasing said rack engaging member.

12. A monkey wrench comprising a shank provided with a fixed jaw, a movable jaw slideable on said shank, a rack associated with said jaw and having teeth extending inwardly, a rack-engaging member mounted in said shank and provided with a plurality of teeth extending outwardly and adapted to engage said rack, a wrench casing inclosing said shank and rack-engaging member and forming a socket within which the rack is adapted to move and means at the top of said casing for releasing said rack engaging member.

13. A monkey wrench comprising a shank provided with a fixed jaw, a movable jaw slideable on said shank, a rack associated with said jaw and having teeth extending inwardly, a rack-engaging member mounted in said shank and provided with a plurality of teeth extending outwardly and adapted to engage said rack, a wrench casing inclosing said shank and rack-engaging member forming a socket within which the rack is adapted to move, a manually-actuated lifter at the top of said casing adapted to engage said rack engaging member and a lip on said casing for guarding against accidental release of the said lifter.

In witness whereof I have signed my name to the foregoing specification in the presence of two subscribing witnesses.

WILLIAM GORDON.
